UNITED STATES PATENT OFFICE.

ALEXANDER T. KOPPE, OF CHICAGO, ILLINOIS, ASSIGNOR TO DIRECTOPLATE CORPORATION, OF CHICAGO, ILLINOIS, A CORPORATION OF ILLINOIS.

PHOTOGRAPHIC LIGHT-TIMING DEVICE.

Application filed November 26, 1923. Serial No. 676,982.

To all whom it may concern:

Be it known that I, ALEXANDER T. KOPPE, a citizen of the United States, residing at Chicago, in the county of Cook and State of Illinois, have invented certain new and useful Improvements in Photographic Light-Timing Devices, of which the following is a specification.

The invention relates to automatic light timing devices particularly adapted for use in photographic printing, and especially adapted for use in connection with machines for making offset press plates, which plates are sensitized and the image photographically produced thereon. Where machines of this character are used, they are usually installed in large printing plants in which elevators, presses and other machines are electrically driven, consequently the voltage of the service line and circuits connected therewith vary inversely with the load, as the various machines are thrown into and out of operation. However to obtain uniformity of exposure of successive prints made on a plate or to obtain prints produced by sufficient time exposure, it is necessary to measure out the light in equal quantity for each successive exposure, or until the required quantity of light has been measured out to produce satisfactory results, therefore it is a primary object of the invention to provide an automatic light timing device, wherein the exposure is lengthened or shortened in time, automatically to compensate for the fall or rise in the voltage of the service line.

A further object is to provide an automatic light timing device which controls a circuit maker and breaker and which device is weight operated and controlled through escapement mechanism as to its speed of operation, said escapement mechanism being controlled in its time of operation through motor means in connection with a circuit in which circuit a photographic light is disposed, and in which circuit the circuit maker and breaker is connected, thereby controlling the light timing device through mechanism driven through a motor, the speed of which varies with the voltage of the circuit, and consequently measuring out successive equal amounts of rays from the light upon variable periods of operation of the timing device during the fluctuation of the voltage.

A further object is to provide an automatic light timing device comprising a rotat-

able drum having connected thereto a flexible member and a weight for rotating the drum in one direction, a handle member having a pawl and carried by the drum, which pawl cooperates with a ratchet wheel, the rotation of which is controlled through a gear train connection with an escapement wheel, the speed of operation of escapement wheel is controlled through the means of an electric motor, which motor is in circuit with a photographic lamp, and the speed of operation controlled by the voltage of the circuit. Also to provide below the weight a normally closed circuit maker and breaker, which circuit maker and breaker is opened by the weight as it is lowered incident to the rotation of the drum.

A further object is to provide a scale having an adjustable stop with which the drum carried lever cooperates when moved in one direction whereby successive exposures of the same duration may be made. However the speed of operation of the device is controlled during successive operations for giving the same light values according to the fluctuation of the voltage in the circuit which carries the photographic light.

With the above and other objects in view the invention resides in the combination and arrangement of parts as hereinafter set forth, shown in the drawings, described and claimed, it being understood that changes in the precise embodiment of the invention may be made within the scope of what is claimed without departing from the spirit of the invention.

In the drawings:—

Figure 1 is a front elevation of the device.

Figure 2 is a top plan view of the device.

Figure 3 is a rear view of the dial plate. 95

Figure 4 is a front elevation of the weight controlling mechanism showing the dial plate removed.

Figure 5 is a vertical transverse sectional view taken on line 5—5 of Figure 4. 100

Figure 6 is a rear view of the weight controlling mechanism, showing the base plate removed.

Figure 7 is a horizontal sectional view taken on line 7—7 of Figure 6. 105

Referring to the drawing, the numeral 1 designates the base of the device, which is adapted to be secured in a vertical position to a support. Secured to the flange 2 of the base 1 by means of screws 3 is a casing 4, 110

which casing is provided with a cover plate 5, which carries a segmentally shaped dial 6, and within the casing and cover plate 5 the weight controlling mechanism is disposed. Rotatably mounted in bearings 7 of the casing 4 and of the bracket 8 is a horizontally disposed shaft 9, on which is rotatably mounted a drum 10, to which is secured at 11, a chain 12. During the operation of the device, during a time exposure, the drum 10 rotates in the direction of the arrow *a*, thereby unwinding the chain 12 under the influence of the weight 13, which is guided in a tubular member 14. The rotation of the drum 10 in the direction of the arrow *a* is entirely controlled by said weight 13 and the speed of rotation of the drum is regulated through mechanism hereinafter set forth. Secured to the shaft 9, preferably rearwardly of the drum 10 is a ratchet wheel 15, which wheel rotates with the shaft 9 and is engaged by a pawl 16, which pawl is pivotally connected at 17 to a hand lever 18. Hand lever 18 is preferably formed integral with the drum 10 and consequently when the pawl 16 is in engagement with the teeth of the ratchet wheel 15, the drum 10 will rotate in the direction of the arrow *a* at the same speed of rotation as the ratchet wheel. Handle member 18 is provided with a depressible member 19, which is connected to the pawl 16, whereby, when it is desired to rotate the drum 10 for restoring the handle member to initial position, said pawl 16 may be moved out of cooperative engagement with the ratchet wheel 15, however if so desired the wheel 10 may be restored by movement in the direction of the arrow *b* by grasping the handle and moving the same in the direction of the arrow *b* at which time the pawl 16 will ratchet over the teeth of the ratchet wheel 15, against the action of the coiled spring 20.

It has been found in making offset press plates that it is necessary to expose the sensitized successive plates to light rays of uniform value. Under this condition it is obvious the periods of exposure of each plate must vary incident to the fluctuating voltage of the line on which the arc lamp 21 is connected, for instance the circuit 22, which may supply electric energy to elevators and various motors in the printing establishment, which motors are thrown into and out of operation at various times as well as the elevator. It is obvious that under these conditions the voltage of the circuit 22 will fluctuate and consequently a period of time necessary for a proper exposure of the sensitized plate would be sufficient for one plate, and would not be sufficient for a succeeding plate. To obviate this difficulty a motor 23 is provided on the panel 1, which motor is in circuit with the service circuit, which supplies energy to the various motors operating

the elevators and motors of machinery in the printing plant, consequently the speed of operation of the motor 23 will vary according to the fluctuations of the voltage on the circuit 22. Motor 23 is provided with a worm 24, which meshes with a worm gear 25, carried by a vertically disposed shaft 26, the upper end of which is provided with a disc 27, to which is pivotally connected at 28 a connecting rod 29. It will be seen that the connecting rod 29 will reciprocate at various speeds according to the speed of operation of the motor 23, which motor will vary in speed of operation according to the voltage on the service line 22. The other end of the connecting rod 29 is pivotally connected at 30 to a horizontally disposed lever 31, which lever is oscillated during the rotation of the disc 27 and consequently oscillates the vertically disposed shaft 32. Shaft 32 extends downwardly into the casing 4 and is provided with spaced escape-
ment lugs 33, which lugs are disposed at opposite sides of the escapement 34 and during the oscillation of the shaft 32 control the rotation of the escapement wheel, the speed of rotation being controlled by the speed of oscillation of the shaft 32, which is in turn controlled from the motor 23. Escapement wheel 34 controls the shaft 9 through a gear train composed of gears 35, 36, 37 and 38; consequently the speed of rotation of the shaft 9 and the ratchet wheel 15 is controlled by the speed of rotation of the escapement wheel 34; therefore the weight 13 can only unwind the chain 12 from the drum 10 at the speed the escapement mechanism allows the ratchet wheel 15, which is connected to the drum 10 by the pawl 16, to rotate.

Secured to the outer face of the cover plate 5 by means of screws 39 is the segmentally shaped scale 6, which scale is arcuate shaped as shown in Figure 2 and has its rear side provided with an internal rack 40, on which is slidably mounted an adjustable stop 41, with which rack the pivoted spring actuated detent 42 cooperates for holding the stop in any position to which it may be moved for positioning its pointer 43 in registration with any of the time graduations 44 on the scale 6. Referring to Figure 1 it will be seen that the stop 41 is positioned whereby its pointer 43 registers with the four minute exposure graduation, and that when the handle member 18 is moved to the right until it is stopped by the stop member 41, a four minute exposure adjustment is made.

The lower end of the tubular guide 14 terminates in a casing 45, in which casing stationary contacts 46 are provided, with which contacts a movable contact 47 cooperates for opening and closing the circuit 22 for lighting the arc lamp 21, and extinguishing the same after a predetermined ex-

posure of the sensitized plate to the light 21 is obtained. Slidably mounted in the lower end of the tubular member 14 is a weight engaging head 48, which head when engaged by the weight 13 and forced downwardly compresses the spring 49, thereby forcing the shaft 50 downwardly and the disc contact 47 out of engagement with the stationary contacts 46, thereby breaking the circuit 22. The circuit 22 is provided with a switch 51 whereby the circuit may be opened or closed as desired and for purposes of illustration a generator 52 is provided for generating current for the circuit.

In operation the first plate is printed after setting the lever 18 at the desired graduation on the scale 6, and closing the switch 51. When the switch 51 is closed, the motor 23 immediately starts to operate and consequently the escapement shaft 32 is oscillated, thereby allowing the gear train, the shaft 9, and the drum 10, through its connection with the ratchet wheel 15, to rotate under the influence of the weight 13. If during the operation the voltage fluctuates in the circuit 22 the speed of rotation of the motor 23 is varied according to the voltage and consequently the speed of rotation of the drum 10 and the downward movement of the weight 13 will vary, and consequently the time of breaking of the circuit by the downward movement of the contact member 47 will vary, thereby allowing the same light values to be given in successive exposures. During the fluctuation of the voltage on the circuit 22, the voltage of the arc light also fluctuates, consequently it will be seen that uniformity of exposure of successive plates is obtained at all times with uniform light values.

From the above it will be seen that an automatic light timing device is provided, particularly adapted for use in connection with sensitized plates on which images are photographically produced, and that periods of exposure for successive plates will be automatically obtained whereby equal light values will be given to successive plates incident to fluctuating voltage on the service circuit, by automatically varying the time of exposure according to the load and fluctuating voltage of the service circuit. It will also be seen that the weight alone is the driving means for the mechanism controlling the circuit maker and breaker, and that the motor 23 only serves to operate escapement mechanism at various speeds according to the fluctuation of the voltage.

The invention having been set forth what is claimed as new and useful is:—

1. The combination with a photographic light circuit, a light carried by said circuit, a circuit maker and breaker carried by said circuit, of an automatically controlled

weight for opening said circuit maker and breaker, and means for controlling said weight in its speed of movement incident to the fluctuating voltage on the circuit.

2. The combination with a photographic light circuit, a light carried by said circuit, of an automatically controlled weight member, said weight member cooperating with a circuit maker and breaker, whereby successive operations of the circuit maker and breaker will vary in time incident to the fluctuation of the voltage of the circuit, thereby allowing successive exposures of uniform value.

3. The combination with a photographic light circuit, a light carried by said circuit, of an automatically controlled weight member, a circuit maker and breaker with which said weight member cooperates, and means controlling said weight whereby successive light exposures of uniform value are obtained at various periods of operation incident to the fluctuation of the voltage on said circuit.

4. The combination with a photographic light circuit, a light carried by said circuit, a circuit maker and breaker carried by said circuit, of a movable weight cooperating with said circuit maker and breaker, escapement mechanism for allowing the movement of the weight into cooperative relation with the circuit maker and breaker, said escapement mechanism being controlled in its speed of operation by a motor in said circuit.

5. The combination with a photographic light circuit, a light carried by said circuit, a circuit maker and breaker carried by said circuit, a vertically movable weight cooperating with said circuit maker and breaker for breaking said circuit, escapement mechanism for controlling the downward movement of said weight, and a motor carried by said circuit and controlling the speed of operation of the escapement mechanism against the action of the weight.

6. The combination with a photographic light circuit, a light carried by said circuit, a circuit maker and breaker carried by said circuit, a vertical movable weight above said circuit maker and breaker and cooperating therewith, a rotatable drum, a flexible member having its end extending over the drum and connected thereto, a shaft, a ratchet wheel carried by said shaft and rotatable therewith, a ratchet pawl connection between the drum and ratchet, escapement mechanism for controlling the speed of rotation of the ratchet, said ratchet controlling the speed of rotation of the drum against the action of the weight, a motor carried by said circuit, said motor controlling the speed of operation of the escapement mechanism.

7. The combination with a photographic light circuit, a light carried by said circuit,

- a vertically movable weight, a circuit maker and breaker with which said weight cooperates and opens upon the downward movement of the weight, said weight being connected to a rotatable drum, a ratchet wheel adjacent said drum, a ratchet connection between said wheel and drum, escapement mechanism controlling the rotation of the ratchet wheel against the weight, a motor carried by said circuit, and controlling mechanism for the escapement mechanism, said controlling mechanism being operated by the motor.
8. The combination with a photographic light circuit, a light carried by said circuit, a circuit maker and breaker carried by said circuit, said circuit maker and breaker comprising a depressible contact cooperating with a stationary contact, of a vertically movable weight disposed above the depressible contact, and means controlled by a motor in said circuit against the action of the weight for varying the time of descent of the weight into contact with the depressible member.
9. The combination with a photographic light circuit, a light carried by said circuit, a circuit maker and breaker carried by said circuit, a suspended vertically movable weight cooperating with said circuit maker and breaker for opening the same upon a downward movement of the weight, escapement mechanism for controlling the speed of downward movement of the weight, and a motor carried by said circuit and controlling the speed of operation of the escapement mechanism according to the fluctuation of voltage on the circuit.
10. The combination with a photographic light circuit controlled through a suspended weight cooperating with a circuit maker and breaker carried by said circuit, of means operated by a motor carried by the circuit for varying the speed of movement of the weight incident to the fluctuation of the voltage on the circuit.
11. The combination with a photographic light circuit controlled by a suspended weight cooperating with a circuit maker and breaker carried by said circuit, escapement mechanism for controlling the movement in one direction of the weight, and a motor carried by the circuit and controlling the speed of operation of the escapement mechanism incident to the fluctuation of the voltage on the circuit.
12. The combination with a photographic light circuit controlled by a suspended weight cooperating with a circuit maker and breaker carried by the circuit, of means for controlling the downward movement of said weight, said means comprising a rotatable drum on which the weight is suspended, a ratchet wheel, a ratchet connection between the drum and ratchet wheel, said weight

forming means for rotating the drum in unison with the ratchet wheel, escapement mechanism controlling the speed of rotation of the ratchet wheel, a motor carried by said circuit, said motor forming means for operating the escapement mechanism.

13. The combination with an electric circuit, a photographic light carried by said circuit, a depressible circuit maker and breaker carried by said circuit, of means for operating said circuit maker and breaker whereby successive light values will be obtained at various periods incident to the fluctuation of voltage on the circuit, said means comprising a vertically movable weight, a rotatable drum, a flexible member connected to the weight and extending over the drum connected thereto, a shaft extending through said drum, a ratchet wheel adjacent said drum, a ratchet connection between the ratchet wheel and the drum whereby the speed of rotation of the drum will be controlled by the ratchet wheel, an escapement mechanism, a gear train connection between the escapement mechanism and the ratchet wheel, a motor in said circuit, said motor controlling the operation of the escapement mechanism against the action of the weight.

14. The combination with an electric circuit, a photographic light carried by said circuit, a circuit maker and breaker carried by said circuit, a suspended weight cooperating with said circuit maker and breaker, cooperating ratchet and drum mechanism rotatable independent of each other in opposite directions and in unison in one direction, escapement mechanism controlling the rotation of the ratchet wheel when the ratchet wheel and drum are rotated in the same direction, and motor driven mechanism in said circuit for controlling the speed of operation of the escapement mechanism.

15. The combination with a photographic light circuit having a fluctuating voltage, a weight controlled circuit maker and breaker carried by said circuit, of means operated by a motor in said circuit for varying the speed of movement of the weight incident to the fluctuation of the voltage on the circuit, thereby allowing successive exposures of uniform value at varying periods of operation.

16. The combination with a light circuit, a light carried by said circuit, a circuit maker and breaker carried by said circuit, timing means independent of said circuit and normally actuated at a uniform speed for opening said circuit maker and breaker at a predetermined time, and means carried by said circuit operating to control and vary the speed of movement of the circuit opening means and influenced in its own speed of movement by the fluctuation of the voltage.

In testimony whereof I affix my signature
ALEXANDER T. KOPPE.
